UNITED STATES PATENT OFFICE.

JOHN WILLIAM PLEASANT, OF VALLEY JUNCTION, IOWA.

COIL WINDER.

Application filed July 10, 1926. Serial No. 121,658.

My invention relates to coil winders of the type adapted to be mounted on a rotating spindle for winding coils and field windings for generators, motors and the like.

5 The purpose of my invention is to provide a coil winder of simple, durable and inexpensive construction.

More particularly, it is my purpose to provide a coil winder, having parts so constructed and arranged as to produce a device having a wide range for winding coils of different lengths, the device being quickly and easily adjustable to any point in its range.

15 Another purpose is to provide such a coil winder having parts so constructed and arranged as to facilitate the speed of winding and handling the coils.

It is a special purpose of my invention to provide in a coil winder novel means for holding the leads, so that they will be out of the way of the winding operation and yet will not be inclined to cause any substantial bend in the wire.

25 In carrying out my purpose, it is my object to provide novel means for holding and threading the wire on the winder.

Still another object is to provide an effective device for shortening the distance between the winding spools for facilitating the easy removal of the finished coils.

Another object is to provide a novel and simple means for quickly and easily adjusting the machine for varying the width of the coils, and simple means for varying the thickness of the coils.

With these and other objects in view, my invention consists in the construction, arrangement and combination of the various parts of my coil winder, whereby the objects contemplated are attained, as hereinafter more fully set forth, pointed out in my claims, and illustrated in the accompanying drawings, in which:

45 Figure 1 is a front elevation of a coil winder embodying my invention.

Figure 2 is a top or plan view of the same.

Figure 3 is a front elevation of the winder installed on an operating machine.

50 Figure 4 is a detail, sectional view taken on the line 4-4 of Figure 1.

Figure 5 is a detail, sectional view taken on the line 5-5 of Figure 1.

Figure 6 is a detail, sectional view taken on the line 6-6 of Figure 5. 55

Figure 7 is a sectional view taken on the line 7-7 of Figure 2.

Figure 8 is a sectional view taken on the line 8-8 of Figure 1.

Figure 9 is a detail view of part of the mechanism at the left-hand end of the device, as shown in Figure 2, showing the parts in a different position. 60

Figure 10 is a detail, sectional view through the rotating shaft members of a 65 slightly modified form of my invention.

Figure 11 is a detail, perspective view of the ends of the shaft members shown in Figure 10; and

Figure 12 is a perspective view of a finished coil made on my winder. 70

In winding coils for generators, convenience in handling the wire and speed of operation are important considerations.

My machine has numerous features, 75 which will be hereinafter especially mentioned, which facilitate the convenient handling of the wire and speed of the coil winding.

A coil winder should also, if possible, have 80 means for holding the leads out of the way of the wire being wound and with such means should not be such as to make any substantial bend in the wire. This feature also is found in my present coil winder as 85 will be seen.

It will be understood that my coil winder is used in connection with a machine having an operating shaft or spindle.

For convenience in explaining the arrangement and operation of my device, I have shown in somewhat diagrammatic form in Figure 3 a machine of the type which can be used with my coil winder. This machine comprises a frame indicated 95 generally in the drawings by the reference character 10. Supported on the machine is a shaft 11 on which is a belt pulley 12.

On the frame 10 is supported also a motor 13 having the belt pulley 14. A belt 100 15 travels on the pulleys 12 and 14 and over the idler pulleys 16. A belt tightener pulley 17 is supported on a swinging arm 18. A rod 19 is connected with the swinging arm 18 and has on it the foot pedal 20, which 105 may be depressed for tightening the belt.

A spring 21 connected with the frame 10 and the arm 18 normally holds the belt tightener pulley 17 in such position as to let the pulley wheel 12 run idle.

5 On the shaft 11 is fixed a gear 22 which meshes with a gear 23 on a shaft 24. On the shaft 24 is a gear 25 meshing with a gear 26 on the operating shaft or spindle 27.

10 For mounting the coil winder on the spindle or shaft 27, I provide what for convenience may be called the spindle head 28. Equi-distantly spaced, rectangular bars 29 are received between their ends in the spindle head 28 and are held in position by a 15 detachable head plate 30.

At one end of the bar 29, to-wit the right-hand end thereof, as shown in Figure 1, a U-shaped shaft journaling member 31 is secured to the bars 29 between their ends in 20 any suitable way.

25 Between the bars 29 are shafts 32 arranged in alignment and having their adjacent ends received in the spindle head 28 as shown in Figure 2. The right-hand shaft 32 has at its outer end a reduced portion 33, shown in Figure 1, extended through the journal 31 and provided on its outer end with a removable head 34. The right-hand shaft 32, as shown in Figure 1, is thus held 30 against longitudinal movement with relation to the bars 29.

35 The left-hand shaft 32 is mounted for limited longitudinal movement for facilitating the removal of the coils after the winding operation.

40 The outer end of the left-hand shaft 32 is shown in Figure 8. It is provided with a reduced spindle 35, which is longer than the spindle 33 above referred to.

45 Between the right-hand ends of the bars 29 is mounted an H-shaped journal member 36 (see Figures 1 and 8) through the central member of which the spindle 35 is extended. A short shaft 38 is rotatably mounted in the outer arms of the journal member 36 and has on it between said arms, the eccentrically mounted cylinder 39.

50 On the outer end of the shaft 38 is the handle 40.

55 A loop or yoke 41 is received between the left-hand ends of the left-hand bars 29 and one end of the yoke 41 is mounted in the right-hand portion of the spindle 35, as shown in Figure 8.

60 The eccentric spindle 39 is so arranged that it may bear against the end of the spindle 35 and against the other end of the yoke 41.

65 On the spindle 35 between the central cross member of the journal member 36, indicated at 36^a in Figure 8, and the right-hand end of the yoke 41, is fixed a collar 42.

70 By manipulating the handle 40 and rotating the shaft 38, the eccentric cylinder

75 39 can be actuated for moving the yoke 41 65 and the left-hand shaft 32 longitudinally for thus varying the position of the left-hand shaft 32.

For locking the parts in position for holding the left-hand shaft 32 at either limit of 70 its movement, there is mounted on the shaft 38 adjacent to the handle 40 a collar 43 having the flat faces 44 and 45 and between them the curved portion 46, as shown in Figure 9.

75 A flat spring 47 is secured to one of the bars 29 for cooperating with the faces 44 and 45 of the collar 43.

80 Adjustably mounted on the bars 29 and the shafts 32 on opposite sides of the spindle head 28 are the winding reels, which are similar except for the features herein-after referred to.

85 The winding reels are indicated generally by the reference characters A and B in the drawings.

90 Each winding reel consists of a cylindrical portion 48 with a flange 49 adjacent to the bars 29. Each winding reel has an extension 50 angular in cross section projected between the bars 29 as shown in Figure 4 and a terminal flange 51, as shown in said figure.

95 The shafts 32 are provided with flat faces 52.

100 In the end of each winding reel, which has the flange 51, is mounted a set screw 53. Between each set screw 53 and one of the shafts 32 is an elongated wear and gripping plate 54, one face of which is flat 100 and abutting against the flat face 52 of the shaft 32, and the other face of which is curved to fit the bore 55 in the extension 50 of the winding reel.

105 It will be understood that the shafts 32 are extended through the bores 55.

110 In each wear and friction or binding plate 54 is a socket 56 to receive the end of the set screw 53, so that the wear and friction plate 54 slides with the set screw and the winding reel.

115 These reels are adjustable longitudinally on the bars 29 and shafts 32 and may be locked or set in any position of adjustment by means of the set screws 53.

120 Each cylindrical portion 48 of each winding coil has at its ends and opposite that provided with the flange 51 an annular flange 57 having a flat face 58.

125 In the end of each cylindrical portion 48 opposite the set screw 53 is a bore or socket 59.

I provide a disc 60 for coacting with the flange 57, so that the coils may be wound between the flanges 57 and the discs 60.

130 Each disc 60 has oppositely extending cylindrical members 61 and 62 of different diameters. The extensions 61 and 62 of

different diameters are provided for winding coils with different spaces between the wires. When the smaller extension 61 is inserted into the bore 59, a bushing 63 is employed, and when the larger extension 62 is inserted, the bushing 63 is removed. The outwardly extending end serves as a handle.

For spacing the disc 60 at different distances from the face 58 of the flange 57 for coils of different thicknesses, I have provided the following means:

It may be noted in a preliminary way that a set screw 64 is mounted in the cylindrical body 48 for locking either of the extensions 61 or 62 in any position of adjustment. For accurately limiting the inward movement of the disc 60, a rod or bolt 65 is slidably but non-rotatably mounted in the flange 57, as shown for instance in Figure 5.

The cylinder 48 has a lateral extension 66 in which is received a sleeve 67 mounted for rotation and internally screw-threaded. The lateral extension 66 (see Figures 2 and 5) has a removable cap 68, for convenience in assembling the parts.

On what may be called the outer end of the sleeve 67 is a knurled flange 69 by the rotation of which the rod 65 may be adjusted.

It will be understood that the inner end of the rod 65 is screw-threaded as at 70 and screwed into the sleeve 67.

For locking the knurled flange 69 against rotation, I mount in the cylinder 48 a locking bolt or the like 71 (see Figures 5 and 6). One end of the bolt 71, as at 72, is threaded to be received and to coact with a threaded socket 73. Intermediate of its ends the bolt 71 is cylindrical, as shown, except that it has a flattened face 74. When the flat face 74 is adjacent to the flange 69, the flange 69 can rotate freely, but when the bolt 71 is rotated by means of the handle 72^a thereon (see Figures 2, 5 and 6), said bolt can be made to frictionally engage and grip and hold the flange 69 and the sleeve 67 against further rotation.

In adjusting the disc 60, the handle 72^a is grasped and the bolt 71 rotated until the flat face 74 is opposite the flange 69. Then the flange 69 is rotated for adjusting the bolt 71 to the proper position. Then the extension 61 or 62 on the disc 60 is inserted into the bore 59 until the disc 60 engages the end of the bolt 65, whereupon the set screw 64 (see Figures 4 and 5) is moved to locking position.

The end of the right-hand winding reel, as shown in Figures 1 and 2, is provided with a slot 75 adjacent to the bore 59.

It should perhaps be noted that the bushing 63 is provided with a hole 76 in its wall to receive the set screw 64, as shown in Figure 4, and is provided with a slot 77 at one

end which registers with the slot 75 when the bushing is installed. The slot 75 extends across the end of the cylinder 48 and across the flange 57 parallel with the rods 29.

The winding reels are the same as heretofore described, except that the left-hand winding reel does not have the slot 75 nor the slot 77 in its bushing 63.

I will now describe the means for engaging and holding the end or ends of the wire being wound, which form the leads.

A rod 78 is slidably extended through the cylindrical body 48 and is locked in its various adjusted positions by means of a set screw 79. (See Figures 2 and 4.) Slidably adjusted on the outer end of the rod 78 is a block 80, which may be locked in various positions of its adjustment by a set screw 81.

A U-shaped support 82 has one arm shorter than the other as shown in Figure 7. The short arm is pivotally mounted by means of a headed stud 83 on the block 80 in such manner that the support 82 may rotate on the stud 83, the axis of which is at right angles to that of the rod 78.

On the longer arm of the support 80, an eccentric cam 84 is rotatably mounted on a stud 85. The cam 84 has the controlling handle 86, shown in Figure 2.

It may be mentioned at this time that the support 82 has a handle 87 for more conveniently manipulating it. (See Figure 2.)

A clamping jaw 88 is mounted on a bolt 89, which is threaded into a lug 90 on the longer arm of the support 82, as shown in Figure 7, whereby the clamping jaw 88 may be adjusted toward or from the eccentric cam 84.

The slot 75 in the cylindrical body 48 of the right-hand winding reel shown in Figures 1, 2 and 3 is designed to receive the leads or ends of a wire or wires 91. In order to prevent the lead from slipping out of the slot 75 toward the disc 60 after the lead has once been received in the slot 75, I provide the following means:

An arm 92 is pivoted at 93 in the flange 49. (See Figure 4.) A spring 94 tends to hold the free end of the arm 92 from the cylindrical body 48.

I provide a slot closing member comprising a cylindrical body 95, having a beveled face 96 and having at its end opposite the beveled face an ear 97 pivoted as at 98 to the free end of the arm 92.

The end of the cylindrical body 95 forms a shoulder with relation to the ear 97 for engaging the arm 92 and limiting the pivotal movement of the cylindrical body 95 with relation to the arm 92 to a slight rocking movement.

For forcing the arm 92 toward the cylindrical body 95 and thus shoving the longer

portion of the cylindrical body 95 into the outer part of the slot 75 and thus closing it for holding the wire 91 in it, I provide the following means:

5 On the right-hand winding reel cylindrical portion 48 is a pair of projecting ears 99. (See Figures 1 and 4.) Journaled in these ears is a short shaft 100 on which is a cam 101. A U-shaped arm 102 is connected with the cam 101 and has at its free end a handle 103 extending away from it at right angles to it. The free end of the U-shaped arm 102 stands adjacent to the free end of the arm 92 when that arm is at the limit of its movement away from the cylindrical portion 48, as shown in Figure 4.

10 Mounted on the arm 92 between it and the eccentric cam 101 is a plate 104, which has an elongated slot 105. The plate 104 is fastened to the arm 92 by means of a screw bolt 106 extended through the slot 105 into the arm 92. The plate 104 has a beveled face 107 for coacting with the cam 101.

15 I will now describe the operation of my improved coil winder and in connection with that description will explain more fully the structure of the device.

20 The wire 91 is wound into a reel 91^a on a suitable drum 108 supported on a shaft 109, which is journaled in a suitable frame 110. A flat, flexible, metal strap 111 or its equivalent is secured at one end to the frame 110 and is extended over one end of the drum 108 and has its free end weighted as at 112, so that it serves as a brake. The winder is mounted on the shaft 27.

25 The extensions 61 or 62 are inserted into the bores 76. According to the width desired for the space 113 between the opposite sides of the coil, the operator uses the extensions 61 or 62. If the extension 61 is used, the bushing 63 is employed.

30 The space between the disc 60 and flange 57 is adjusted according to the thickness of the coil desired. This is done by adjusting the bolt 65 by means of the sleeve 67 and knurled flange 69 (see Figure 5), and the locking of the bolt 65 by means of the locking bolt 71. (See Figures 5 and 6.)

35 The winding reels are adjusted on the bars 29 by loosening the set screws 53 and adjusting the winding reels longitudinally of the bars. One of each of the bars is graduated as indicated at 114 (see Figure 2), and the flanges 51 are each provided with two pointer fingers 115, which are spaced from each other corresponding to the difference in diameter of the respective extensions 62 and 61.

40 The winding reels are then locked in position by means of the set screws 53. This adjustment of the winding reels determines the length of the finished coil 116.

45 The rod 78 is then adjusted in its cylindrical body 48 and locked in position by means of the set screw 79 according to the length of the lead 117 (Figure 12) that may be desired.

50 The winder is then swung around until the right-hand end thereof shown in Figures 1 and 2 is adjacent the reel 91^a, and the ends of the wire or wires are clamped between the jaw 88 and the cam 84. The jaw 88 is adjusted according to the diameter of the wire being used, and the cam 84 is swung over by means of the handle 86, for clamping the wire between it and the jaw 88.

55 The foot pedal 20 is then pressed downwardly for tightening the belt 15 for slowly swinging or rotating the winder.

60 When the winder is swung about a half revolution to the position shown in Figure 3, the operator pushes the wire 91 toward the winder. The wire will slide down over the U-shaped arm 102 into the space between the disc 60 and the flange 57 (see Figure 4).

65 It will be remembered that when the half revolution of the winder has taken place, the slot 75 will be up and on account of the fact that the operator has pushed the wire 91 toward the winder, the wire will slip into the slot as shown in Figure 4.

70 The operator then quickly grasps the handle member 103 and swings the U-shaped arm 102 from its position shown in full lines in Figures 3 and 4 to its position shown in dotted lines in said figures.

75 The cam 101 will engage the beveled face 107 of the plate 104 and force the arm 92 toward the cylindrical body 48 for moving the cylindrical member 95 to position for closing the slot 75, as shown by dotted lines in Figure 4, and preventing the lead from sliding into the space between the flange 57 and the disc 60.

80 As the rotation of the winder continues the coil will be formed.

85 On account of the fact that the U-shaped member 82 is rotatably mounted on the block 80, the wire is not twisted in any way.

90 When the coil has been completed, the wire is severed at the proper point for providing both leads or sets of leads and the end of the wire from the reel is again clamped between the jaw 88 and the eccentric cam 84.

95 The operator then removes the finished coil by loosening the set screws 64. He then swings the handle 40 around (see Figures 1 and 2) for rotating the eccentric 39 from its full line position shown in Figure 8 toward its dotted line position shown in said figure, whereupon the left-hand rod 32 shown in Figure 1 will be moved longitudinally toward the right, carrying with it the yoke 41 for loosening the coil on the extension 61 or 62 as the case may be.

The projecting extensions 61 or 62 may be grasped for removing the discs 60 and taking off the finished coil. The discs 60 are then replaced in position and another coil 5 can be wound.

A great advantage in the present device arises from the speed with which it may be operated for winding the coils. The convenience in manipulating the parts contributes, of course, to such speed.

It will be noted in the form of the device heretofore described, the winding reels are adjusted slidably on the bars 29 and rods or shafts 32.

In Figures 10 and 11, I have shown a slightly different way of adjusting the winding reels toward or from each other. This form of my invention is also provided with the means illustrated in Figures 8 and 9 for releasing the tension on the wound coil by moving left hand spool 48 toward the center.

The shafts 32^a are threaded as at 118 for a considerable portion of their length. One of the shafts is provided with a slot 119 and the other with a tongue 120 slidable in said slot and the shafts are arranged with their ends having such slot and tongue received in the spindle head 28.

The cylindrical bodies 48 of the winding reels have threaded portions 121 receiving the threaded portions 118 of the shafts 32^a.

On the ends of the shafts are crank handles 122, so that by rotating the shafts, the winding reels may be moved toward or from each other.

It will be understood that the shafts are provided respectively with right-hand and left-hand screw threads.

The left-hand shaft 32^a is bodily movable 40 lengthwise in the same manner as the left-hand shaft 32 shown in Figure 1.

Some changes may be made in the arrangement and construction of the various parts of my coil winder, without departing from the real spirit and purpose of my invention, and it is my intention to cover by my claims 45 any modified forms of structure or use of mechanical equivalents, which may be reasonably included within their scope.

I claim as my invention:

1. In a coil winder, a pair of spaced bars, means for mounting them on a shaft, aligned shafts supported on said bars, winding reels mounted on said bars for adjustment toward and from each other, means for locking said reels on said shafts, one of said shafts being mounted for longitudinal adjustment, a wire clamp, and means for adjustably mounting the wire clamp for rotation at different distances from the winding reels.

2. In a device of the class described, a support, winding reels mounted thereon for adjustment toward and from each other, a wire clamp, and means for mounting the wire clamp on one of the reels for adjustment

to different distances from that winding reel, one of said reels having a wire receiving slot.

3. In a device of the class described, a support, winding reels mounted thereon for adjustment toward and from each other, a wire 70 clamp, and means for adjustably mounting the wire clamp for rotation at different distances from the winding reels, one of said reels having a wire receiving slot, and means for guiding wire to one of the reels. 75

4. In a device of the class described, a support, winding reels mounted thereon for adjustment toward and from each other, a wire clamp, and means for adjustably mounting the wire clamp for rotation at different 80 distances from the winding reels, one of said reels having a wire receiving slot, and adjustable means for retaining wire in the slot.

5. In a device of the class described, a support, winding reels mounted thereon for adjustment toward and from each other, said reels, each having a body with a bore and a disc with oppositely projecting extensions 90 of different diameters, either of which may be projected into the bore.

6. In a device of the class described, a support, winding reels mounted thereon for adjustment toward and from each other, said reels each having a body with a bore and a disc with oppositely projecting extensions of different diameters, either of which may be projected into the bore, and means for locking either extension in centered position in the bore. 100

7. In a device of the class described, a support, winding reels mounted thereon for adjustment toward and from each other, said reels each having a body with a bore and a disc with a part received in the bore, the body of one reel having a slot communicating with the bore, for receiving a lead, and means for holding the lead in the slot. 105

8. In a device of the class described, a support, winding reels mounted thereon for adjustment toward and from each other, said reels each having a body with a bore and a disc with a part received in the bore, one body having a slot adjacent to said bore for leads. 110

9. In a device of the class described, a support, winding reels mounted thereon for adjustment toward and from each other, said reels each having a body with a bore and a disc with a part received in the bore, one body having a slot adjacent to said bore for leads, and adjustable means for closing said slot. 120

10. In a device of the class described, a support, winding reels mounted thereon for adjustment toward and from each other, a rod mounted in one of said reels parallel with said support, and a clamping means rotatably mounted on said rod. 125

11. In a device of the class described, a 130

- support, winding reels mounted thereon for adjustment toward and from each other, a rod mounted for longitudinal adjustment in one of said reels parallel with said support, and a clamping means rotatably mounted on said rod.
12. In a coil winder, a pair of spaced bars, means for mounting them on a shaft, aligned shafts supported on said bars, winding reels mounted on said bars for adjustment toward and from each other, means for locking said reels on said shafts, said shafts having flat faces, said winding reels adjustably mounted on the shafts between the bars.
13. In a coil winder, a pair of spaced bars, means for mounting them on a shaft, aligned shafts supported on said bars, winding reels mounted on said bars for adjustment toward and from each other, means for locking said reels on said shafts, said shafts having flat faces, said winding reels adjustably mounted on the shafts between the bars, and means for adjusting one of the shafts with its reel.
14. In a device of the class described, a support, winding reels mounted thereon for adjustment toward and from each other, said reels each having a body with a bore and a disc with oppositely projecting extensions of different diameters, either of which may be projected into the bore, and a filler bushing for the bore for receiving the extension of smaller diameter.
15. In a device of the class described, a support, winding reels mounted thereon for adjustment toward and from each other, said reels each having a body with a bore and a disc with oppositely projecting extensions of different diameters, either of which may be projected into the bore, and a filler bushing for the bore for receiving the extension of smaller diameter, one body and its bushing having corresponding slots to receive a lead.
16. In a coil winder, a shaft, a support mounted thereon, reels on the support, one reel having a body with an annular flange and a bore concentric therewith, a disc having a cylindrical extension projectable into the bore, and a set screw for locking the extension in the body, whereby the set screw may be loosened and the disc removed with the coil on said extension, so that the extension may then be slid out of the coil.
17. In a coil winder, a support, winding reels thereon, each comprising a body and a bore and a disc having oppositely projecting members, either of which members may be received in the bore, means for securing said members in the bores, whereby upon the releasing of said means the discs may be removed by grasping the outer extending members carrying with them the coil mounted on the inner extending members.
18. In a coil winder, a shaft, a support mounted thereon, reels on the support, a lead clamp mounted to move bodily with the reels and to rotate with relation thereto, whereby when a lead is gripped by the clamp and the winder is operated, the wire will be wound on the reels without being improperly twisted between the lead clamp and the adjacent reel.
19. In a coil winder, a pair of aligned shafts, means for supporting the shafts, winding reels adjustably mounted on the shafts, and means for bodily adjusting one of the shafts lengthwise independently of the other.
20. In a coil winder, a frame comprising side and end members, a head plate fixed to the frame, a pair of aligned rods having their adjacent ends slidably and rotatably mounted in the head plate and slidably and non-rotatably connected with each other, one rod being rotatably but non-slidably mounted in the frame and the other being rotatably and slidably mounted in the frame, and winding reels having threaded connections with the rods and slidable mounting on the frame.
21. In a coil winder, a frame comprising side and end members, a head plate fixed to the frame, a pair of aligned rods having their adjacent ends slidably and rotatably mounted in the head plate and slidably and non-rotatably connected with each other, one rod being rotatably but non-slidably mounted in the frame and the other being rotatably and slidably mounted in the frame, means for independently, longitudinally adjusting the last-named rod in the frame, and winding reels having threaded connections with the rods and slidably mounted on the frame.
22. In a coil winder, a frame, comprising side and end members, a head plate fixed to the frame, a pair of aligned rods having their adjacent ends slidably and rotatably mounted in the head plate and slidably and non-rotatably connected with each other, one rod being rotatably but non-slidably mounted in the frame and the other being rotatably and slidably mounted in the frame, and winding reels having threaded connections with the rods and slidable mounting on the frame, the threaded connections being such that the rotation of one rod serves to simultaneously adjust the reels toward or from each other.
23. In a device of the class described, a support, winding reels adjustably mounted thereon, each reel having a body with a bore, a disc having a cylindrical extension for reception in the bore, an adjustable gauge mounted on the body for coacting with the cylinder for accurately fixing its distance from the body, and means for locking the bore in the body.
24. In a device of the class described, a movable support, winding reels mounted thereon, one of said reels having adjacent

to its part of smallest diameter a slot to receive a lead and a wire clamp on said support.

25. In a device of the class described, a rotatable support, winding reels mounted thereon, one of said reels having adjacent to its part of smallest diameter a slot to receive a lead, adjustable means for closing the entrance to said slot and a clamp for the other lead.

26. In a device of the class described, a rotatable support, winding reels mounted thereon, one of said reels having adjacent to its part of smallest diameter a slot to receive a lead, and adjustable means for closing the entrance to said slot, said means including an actuating member adapted when in one position to serve as a guide.

Des Moines, Iowa, June 9, 1926.
JOHN WILLIAM PLEASANT.
